P. L. JOSLYN

INTERNAL COMBUSTION ENGINE

Filed Oct. 11, 1926

INVENTOR.

P. L. JOSLYN

BY

Victor J. Evans

ATTORNEY.

UNITED STATES PATENT OFFICE.

PAUL LEO JOSLYN, OF SAN FRANCISCO, CALIFORNIA.

INTERNAL-COMBUSTION ENGINE.

Application filed October 11, 1926. Serial No. 140,972.

This invention relates to improvements in internal combustion engines, and has particular reference to that type of engine wherein liquid fuel is injected into the cylinder in 5 counter-distinction to the type of engine wherein a gaseous fuel is compressed and exploded by a spark or other ignition medium.

The principal object of this invention is to 10 produce an internal combustion engine wherein a charge of liquid fuel is injected into the cylinder at a time when the piston reaches the inner end of the compression stroke, the air having been admitted to the 15 cylinder previous to the compression stroke, thus resulting in the igniting of the fuel as soon as the same is injected into the cylinder.

A further object is to produce a condition 20 within an engine which will permit the perfect combustion of a heavy fuel over long periods of time.

Another object is to produce an engine 25 which eliminates the employment of complicated mechanism commonly employed in engines of this type.

A further object is to produce means whereby a standard form of engine may readily be converted into an engine employing 30 my invention.

A still further object is to provide means whereby a perfect scavenging of the ignition chamber may be accomplished.

Other objects and advantages will be apparent during the course of the following 35 description.

In the accompanying drawings forming a part of this specification, and in which like numerals are employed to designate like 40 parts throughout the same,

The figure is a fragmentary detail view of the upper end of the piston and cylinder having my invention applied thereto.

It has been common to employ internal 45 combustion engines utilizing liquid fuel of the solid injection type, but it has been found from experience that engines of this type lose as high as forty per cent of their power through the imperfect combustion and scavenging, and consequently it is necessary to build much larger engines in order to secure a given horse power.

I have therefore provided an engine where- 50 in it is possible to secure perfect combustion by setting up therein certain currents of air

which not only assist in making a perfect combustion throughout the explosion period, but also assist in producing a perfect scavenging.

In the accompanying drawings wherein 60 for the purpose of illustration is shown a preferred embodiment of my invention, the numeral 5 designates the customary cylinder of an internal combustion engine and the numeral 6 a piston adapted to be reciprocated therein. Upon the cylinder 5, I position a head 7 having the customary water jacket 8. Within the member 7 I preferably form a conical-shaped combustion space 9. The member 7 may be secured to the piston 70 5 in any approved manner.

A boss 11 formed upon the head 7 is adapted to accommodate a jet plug 12 which may be secured therein in any desired manner. This plug has a tip 13 which extends 75 into the combustion chamber 9 quite an appreciable distance.

By viewing the figure it will be seen that the contour of the plug 12 is such that when it is placed in position, the wall thereof 80 joins the wall of the combustion chamber in such a manner as to form a semi-circular cavity at all points around the plug.

It will also be noted by viewing the figure that the position of the tip is such that 85 oil issuing from the nozzle 14 in the form of a spray, will have its boundary parallel to the walls of the combustion chamber, the reason for which will be later seen. The nozzle 14 carried in the block 12 is fed by a 90 passage 16 extending upwardly into the valve housing 17 within which a valve is positioned while a pipe 18 conducts fuel oil to the housing 17.

The operation of my engine is as follows:—

When the piston 16 is at its lowest point of travel, assuming that a two cycle engine is being used, air will be interposed at a 100 point adjacent the top of the piston after which upward movement of the piston will compress the air into the combustion chamber 9. At the time that the piston has reached the upper end of its stroke, the oil supply will function so as to overcome the 105 valve in the valve chamber 17 with the result that oil will be forced through the passage 16 and through the nozzle 14 into the combustion chamber 9.

As the spray issuing from the nozzle 110

moves downwardly toward the head of the piston a circulation of air in the combustion chamber will take place as indicated by the arrows, with the result that as the burning of the oil commences, fresh air will be brought to this point of burning resulting in a more efficient combustion of the oil and consequently greater power from a given amount of fuel will result.

10 The piston will now be drawn downwardly in the customary manner, after which the exhaust port will be opened and the exhaust gases will pass therefrom.

15 In the next cycle the same operation will take place, but it will be noted that the circulation of air above described will have cleaned out any burnt gases which may have become pocketed at a point adjacent the nozzle. Therefore, it will be seen that it is 20 impossible for the accumulation of any appreciable amount of burnt gas to exist within the combustion chamber at any given point.

25 In a four cycle engine it is of course obvious that the air and exhaust ports will be mechanically operated, employing the customary valves common to four cycle engines.

30 It will thus be seen that I have provided an efficient and simple means for effecting

a perfect combustion at a point adjacent the nozzle of an engine of the character described.

It is to be understood that the form of my invention herewith shown and described is to be taken as a preferred example of the same, and that various changes relative to the shape, size and arrangement of parts may be resorted to without departing from the spirit of the invention or the scope of 40 the subjoined claim.

Having thus described my invention, I claim:—

45 In an internal combustion engine, a combustion chamber formed therein, a jet positioned within said combustion chamber and extending thereinto a substantial distance, the shape of said combustion chamber conforming to the shape of the spray issuing from said jet, the cross-sectional area of said 50 chamber being greater than the cross-sectional area of said spray so as to provide an air space surrounding said spray, the walls of said jet and the walls of said combustion chamber joining in such a manner 55 as to form a semi-circular cavity at all points around said jet.

In testimony whereof I affix my signature.

PAUL LEO JOSLYN.
